UNITED STATES PATENT OFFICE.

FRANKLIN F. CHANDLER AND RAYMOND E. YOUNG, OF LA FAYETTE, INDIANA, AS-SIGNORS TO ROSS GEAR & TOOL COMPANY, OF LA FAYETTE, INDIANA, A CORPORATION OF INDIANA.

STEERING-POST CONTROL.

Application filed December 16, 1926. Serial No. 155,190.

Our invention is a novel improvement in control assemblies for steering gears of automobiles, and its object is to provide simple and novel means for frictionally holding the 5 various control levers in any adjusted position and for limiting the extent of arcuate movements of said control levers.

The invention is an improvement upon the lever control shown in the co-pending 10 application of Gruenewald and Ross, Serial No. 148,554, filed November 15, 1926; and a further object of the invention is to simplify and improve said control and to enable more than two control levers to be very read- 15 ily assembled and frictionally held in any adjusted position.

The accompanying drawings illustrate one practical embodiment of the invention, and we will explain the same with reference 20 thereto to enable others to adopt and use the same; and will summarize in the claims the novel features of construction, and novel combination of parts, for which protection is desired.

25 In said drawings,—

Fig. 1 is an elevation partly in section of the lower end of a steering gear equipped with our improved frictional devices for holding the control levers in adjusted positions, and for limiting the movement of said 30 levers.

Fig. 2 is a bottom plan view of Fig. 1;

Fig. 3 is a cross-sectional view on the line

3—3, Fig. 1;

35 Fig. 4 is a detail of the spacing plate.

Fig. 5 illustrates a slight modification of the spring hanger.

The invention is readily adaptable to a 40 large variety of forms of steering gears, but is illustrated herein as applied to a steering gear of the type shown in Ross Patent No. 1,567,997 of Dec. 29, 1925.

In the drawings we have shown three 45 nested control tubes C, C¹, C² which are ar- ranged one within the other, and extend through the steering shaft (not shown) and the gear case G at the lower end of the steering shaft, and project below the lower end of the gear case as shown; and tube C¹ projects below tube C, and tube C² projects 50 below tube C¹.

The control tubes may be turned by any suitable means (not shown) attached to the upper end of the tubes in position to be

readily engaged by the fingers of the opera- 55 tor in the usual manner, and as shown and described in the aforesaid application. So far the constructions described are common and may be of any suitable kind, and are not 60 features of the present invention.

Our present invention provides novel 65 means for frictionally holding each control tube and lever in any adjusted position, and for limiting the arcuate movement of such control lever. For this purpose a lever 1 is attached to the lower end of the spark 70 control tube C which projects through and below the lower part of the gear casing G; to the lower end of tube C¹ is attached a similar lever 1^a, and to the lower end of tube C² is attached a similar lever 1^b. Each of the levers 1, 1^a, 1^b, preferably has a spit hub 75 which may be clamped onto the lower end of the tube by a screw 1^s.

The free end of lever 1 may be connected 75 by any suitable means to the usual spark ad- justing device (not shown). The free end of lever 1^a may be connected by any suit- 80 able means to the throttle adjusting device (not shown); and the free end of lever 1^b may be connected by any suitable means to the light controlling switch (not shown).

Interposed between the hub of the lever 1 and the underside of the gear case G is a 85 frictional washer 2 of any suitable material. A similar frictional washer 2^a is interposed between lever 1^a and a non-rotatable plate 3 which is shown as having a circular head axially perforated for the passage of the tube C¹, and a laterally projecting arm 3^a, 90 the end of which is notched to engage the side 5^a of a U-shaped hanger 5 attached to the lower end of the gear case G. A similar frictional washer 2^b is interposed between lever 1^b and the lower member 5^b of the 95 said hanger 5.

As shown a spacing collar 4 is interposed 100 between the levers 1 and 1^a, said collar loosely surrounding the tube C; and a sim- ilar collar 4^a is interposed between the lower side of plate 3 and the lever 1^b, said collar loosely surrounding the tube C¹.

The hanger 5 is shown as being U-shaped 105 and the upper ends of its parallel side por- tions 5^a are secured by tap bolts 5^e to lugs G⁴ on the lower portion of the gear case G. This hanger has a central aperture 5^c in its lower member 5^b to receive the lower end of

2
tube C² when the hanger is attached to the housing G. The side members 5^a of the hanger serve as stops to limit the swinging movement of levers 1, 1^a, and 1^b. The side members 5^a of the hanger are preferably provided with bends 5^a which impart a longitudinal resiliency or elasticity to the legs 5^a. Instead of one bend, the side members 5^a might be formed with a plurality of bends 10 or corrugations as illustrated in Fig. 5, the essential feature being the stiff longitudinal resiliency thereof.

The total unassembled length of the side members or legs 5^a is made somewhat less 15 than the total space required by the complete assembly of the three levers, friction washers, the spacer collars, and plate, so that when all the parts are assembled, and the screws 5^e screwed down tightly, the legs 5^a 20 will be slightly extended and will act as springs, due to the bends or corrugations therein, and such resiliency of legs 5^a establishes sufficient pressure upon the levers, friction washers, and spacer collars between 25 bar 5^b and case G, to insure that the levers 1, 1^a, 1^b will be held in any adjusted position. The same amount of friction is exerted on each of the levers 1, 1^a, 1^b because of their 30 contact with the friction washers as described.

The turning of lever 1 is resisted by the friction washer 2 which contacts with the lower part of the housing G and is non-rotatable or stationary. The resistance of 35 lever 1^b to turning is produced by friction washer 2^b lying between it and the stationary part 5^b of the hanger. The resistance of lever 1^a is provided by friction washer 2^a engaging the non-rotatable plate 3. When 40 lever 1^a is rotated, plate 3 remains stationary, although said plate is not rigidly attached to the hanger, said plate being held from rotating, but is perfectly free to move up or down. Hence the frictional pressure 45 produced by the spring action of the hanger 5 will be uniformly transferred to the various levers, so that the same amount of friction is produced by such spring action of the hanger to resist the rotation of each of the 50 levers 1, 1^a, 1^b.

Forming the hanger 5 as above described with the resilient legs 5^a does not appreciably increase its cost, since by using such hangers the usual coil springs described and shown in 55 the application aforesaid are eliminated.

The construction permits any control tube and lever to be turned without turning, or tending to turn, any other control tube and lever. Obviously the number of control 60 tubes and levers used can be varied according to the number of different controls which it is desired to have assembled at the center of the steering column.

We do not consider our invention limited 65 to the exact forms shown in the drawings

for obviously changes may be made therein within the scope of the claims.

We claim:

1. In combination with a steering post, a control tube; a lever attached to the lower end of the control tube; frictional means for holding the lever, and a resilient hanger attached to the post below the tube for holding said means in frictional contact. 70
2. In devices as set forth in claim 1,— said hanger also limiting the rotatorial movement of the lever. 75
3. In combination with a steering post, a plurality of nested control tubes extending through the post, a lever attached to the lower end of each control tube; frictional members respectively engaging the levers; and a resilient hanger attached to the lower end of the post for holding said members and levers in frictional contact. 80
4. In devices as set forth in claim 3,—said hanger also limiting the rotatorial movements of the levers. 85
5. In a control assembly as set forth in claim 3, spacers interposed between the levers. 90
6. In a control assembly as set forth in claim 3, a non-rotating plate interposed between the levers. 95
7. In a control assembly as set forth in claim 3, spacers interposed between the levers, and a non-rotating plate interposed between the levers. 100
8. In combination with a steering post, a plurality of control tubes extending through the lower end of the post; a lever attached to the lower end of each control tube; a frictional member for each lever; a U-shaped hanger attached to the gear case, and having resilient legs holding said levers and members in position, and also holding the members in frictional pressure contact. 105
9. In mechanism as set forth in claim 8, said hanger also limiting the rotatorial movement of the levers. 110
10. In a control assembly as set forth in claim 8, spacers interposed between the levers. 115
11. In a control assembly as set forth in claim 8, a non-rotating plate interposed between the levers. 120
12. In a control assembly as set forth in claim 8, spacers interposed between the levers, and a non-rotating plate interposed between the levers. 125
13. In combination with a gear case, a plurality of control tubes extending through the gear case; a lever attached to the lower end of each control tube; a frictional member for each lever; a U-shaped hanger attached to the gear case; a plate interposed between the levers, and non-rotatably engaged with the hanger, said hanger having resilient legs and holding the levers and frictional members in operative relation and also providing 130

yielding pressure contact between the levers and frictional members.

14. In a control assembly as set forth in claim 13, spacers interposed between the levers.

15. In a control assembly as set forth in claim 13, spacers interposed between the levers.

16. In a control assembly as set forth in claim 13, spacers interposed between the levers.

vers, and a non-rotating plate interposed between the levers, substantially as described.

17. A U-shaped hanger for a control assembly having extensible resilient legs substantially as and for the purpose set forth. 15

In testimony that we claim the foregoing as our own, we affix our signatures:

FRANKLIN F. CHANDLER.
RAYMOND E. YOUNG.
